CLAIM

I claim the ornamental design for an arm chair, as shown and described.

DESCRIPTION

FIG. 1 is a perspective view of my arm chair;

FIG. 2 is a front elevation view thereof;

FIG. 3 is a rear elevation view thereof;

FIG. 4 is a right side elevation view, the left side elevation

view (not shown) is a minor image thereof;

FIG. 5 is a top plan view thereof;

FIG. 6 is a close up view of the area designated “6” in FIG. 2;

FIG. 7 is a close up view of the area designated “7” in FIG. 6; and,

FIG. 8 is a close up view of the area designated “8” in FIG. 1.
